Edwin Drewitz, Long Island City, N. Y., assignor
to Metropolitan Electric Mfg. Co., Long Island
City, N. Y.

Application September 8, 1949, Serial No. 4,908

Term of patent 14 years

(Cl. D26—1)

To all whom it may concern:

Be it known that I, Edwin Drewitz, a citizen of the United States of America and a resident of Long Island City, in the county of Queens and State of New York, have invented a new, original, and ornamental Design for an Operating Handle, of which the following is a specification, reference being had to the accompanying drawings, forming part thereof.

Fig. 1 is an elevational view of an operating handle, showing my new design.

Fig. 2 is a side view of same.

Fig. 3 is a top plan of the same.

I claim:

The ornamental design for an operating handle, as shown.

EDWIN DREWITZ.
